UNITED STATES PATENT OFFICE.

DICK F. BUSSKOHL, OF PEDRO, SOUTH DAKOTA.

BELT GUIDE AND STAY.

1,410,549.

Specification of Letters Patent. Patented Mar. 28, 1922.

Application filed July 15, 1919, Serial No. 310,900. Renewed September 13, 1921. Serial No. 500,425.

To all whom it may concern:

Be it known that I, DICK F. BUSSKOHL, a citizen of the United States, residing at Pedro, in the county of Pennington and 5 State of South Dakota, have invented certain new and useful Improvements in Belt Guides and Stays, of which the following is a specification.

In the operation of agricultural machinery, such as threshers, hullers and the like, 10 a portable traction engine is generally employed in the open and a crossed drive belt is utilized as means for transmitting power from the traction engine to the mechanism 15 to be driven. When the wind is blowing considerable difficulty is experienced in maintaining the drive belt in operative position and particularly is this the case when the wind is blowing in a direction to exert 20 a pressure against a side of the belt. As a result there is a tendency to cause displacement of the drive belt from the pulleys of the engine and machine being driven.

The present invention provides means for 25 sustaining the drive belt against the pressure of the wind so as to hold the belt upon the pulleys of the engine and machine being operated. In accordance with this invention a guide or stay of peculiar form is 30 provided and staked to the ground opposite the point of crossing of the runs of the belt and upon the side thereof to sustain the belt against the pressure of the wind.

The drawing illustrates a preferred embodiment of the invention. However, it is 35 to be understood that in adapting the same to meet different conditions, various changes in the form, proportion, and minor details of construction may be resorted to without 40 departing from the nature of the invention as claimed hereinafter.

Referring to the accompanying drawing,

Fig. 1 is a front view of a belt guide or 45 stay having two of the rollers in line.

Fig. 2 is a view similar to Fig. 1 turned so as to disclose the three rollers.

Fig. 3 is a horizontal section on the line 3—3 of Fig. 2 looking upward as designated by the arrows.

Fig. 4 is a detail view showing the application of the invention.

Corresponding and like parts are referred to in the following description and indicated in the several views of the drawing by like 55 reference characters.

The device comprises like plates 1, tie rods 2 connecting the plates and rollers 3 which are journaled at their ends in the plates 1. It has been found that three rollers give the best results when disposed, 60 as indicated most clearly in Fig. 3, that is, about in line with the angles of an equilateral triangle. The plates 1 are of like formation and each is of the form of an equi-lateral triangle and is provided with 65 a plurality of openings 4 to receive pins or stakes 5, whereby the device may be firmly secured to the ground when in operative position. Both ends of the device being alike, it is obvious that either end may be staked to 70 the ground when in service. The tie rods 2 have their end portions threaded and passed through openings in the plates 1. A pair of binding nuts 6 are mounted upon each end of each of the tie rods and serve 75 to secure the plates 1 in the required adjusted position. The rollers 3 may be of any form and are journaled at their ends to the angular portions of the plates, exterior to and adjacent the respective tie rods 2. 80 It is to be understood that the plates 1 may be of any construction and that the tie rods and rollers may be of any length depending upon the particular use of the device.

In Fig. 4, the numeral 7 designates the 85 drive pulley of a portable traction engine and 8 the driven pulley of the thresher or other machine to be driven. These two pulleys are connected by means of a drive belt 9 which as shown is crossed midway 90 of its ends. It will thus be understood that the middle portion of the drive belt presents a relatively large surface for the action of the wind. The letter A designates a guide or stay disposed upon the leeward 95 side of the drive belt opposite the point of crossing and is securely staked to the ground by pegs or stakes driven through the openings of the lowermost plate. The device is so placed that one or two of the pulleys 100 3 are in contact with the leeward side of the drive belt so as to sustain the same against the action of the wind and prevent any tendency to displacement of the drive belt from either one or both of the pulleys 105 7 and 8.

The foregoing description and the drawing have reference to what may be considered the preferred, or approved form of my invention. It is to be understood that 110

I may make such changes in construction and arrangement and combination of parts, materials, dimensions, et cetera, as may prove expedient and fall within the scope of the appended claim.

Having thus fully described my invention, what I claim as new and desire to secure by Letters Patent is:—

A belt guide and stay, comprising spaced plates having the form of an equi-lateral triangle and provided with openings for the

reception of pegs or stakes, tie rods adjustably connecting the plates adjacent the angles thereof, and rollers journaled between the plates at the angles thereof, exterior to and adjacent the tie rods. 15

In testimony whereof I affix my signature in presence of two witnesses.

DICK F. BUSSKOHL.
